UNITED STATES PATENT OFFICE.

WILLIAM MCCLAVE, OF SCRANTON, PENNSYLVANIA, ASSIGNOR TO MCCLAVE-BROOKS COMPANY, OF SCRANTON, PENNSYLVANIA, A CORPORATION OF PENNSYLVANIA.

STEAM-TURBINE BLOWER.

1,328,286.

Specification of Letters Patent. Patented Jan. 20, 1920.

Application filed August 24, 1918. Serial No. 251,308.

To all whom it may concern:

Be it known that I, WILLIAM MCCLAVE, a citizen of the United States, residing at Scranton, in the county of Lackawanna and State of Pennsylvania, have invented certain new and useful Improvements in Steam-Turbine Blowers; and I do hereby declare the following to be a full, clear, and exact description of the same, reference being had 10 to the accompanying drawings, forming part of this specification.

This invention relates to steam turbine blowers of that type wherein the rotor of the turbine is rigidly connected with the impeller of the blower and rotates in unison therewith, the objects of the invention being to improve upon and overcome difficulties found to exist in the turbine blower disclosed in my prior Patent No. 1,165,796, dated Dec. 20, 1915, particularly in providing a sealing and leakage arresting means for the common shaft of the turbine blower and rotor that will be self-adjusting to meet the exact alignment of the shaft by moving up and down or 25 sidewise, as may be necessary.

A second object is the provision in such a seal of means to form a practically tight joint at each end of the seal and yet have an open space centrally thereof to permit any 30 exhaust steam or water of condensation which may pass from the rotor exhaust chamber, to be thrown off by the rapidly revolving shaft into the suctional exhaust chamber and carried off by the means shown 35 in the drawings, thereby preventing any of said steam or water from passing into the ball bearing chamber of the blower or of the opposite end of the shaft.

A further object is the provision of such 40 sealing and leakage arresting means so located as to permit the cooling of the shaft centrally of the seal by a current of air which in itself assists in the carrying away of the steam and condensate and the diversion of same from the journal bearings. This constantly moving current of cold air which 45 passes through the suctional exhaust chamber serves the purpose of not only helping to keep the carbon cylinders cool and carrying away the steam and condensate, but also 50 cools the shaft itself, together with the immovable shoulder against which the outer ends of the carbon cylinders rest.

Referring now to the accompanying drawings, 55

Figure 1 is a sectional elevation of my device taken in a vertical plane longitudinally of the axis of the rotor and impeller shaft.

Fig. 2 is an enlarged view of one of the 60 bearings for the shaft.

Fig. 3 is a vertical sectional view taken on the line 3—3 of Fig. 2.

The casing 1 is generally cylindrical in form and is adapted to be built into the wall of a steam boiler furnace, usually in the ash-pit thereof. This casing supports the two-piece rotor housing by means of distance pieces 2 and also by means of the connection (not shown) with the exhaust pipe 3 rigidly secured to the lower part of the rotor 70 housing.

In the fluid chamber 4, between the outer and inner parts of the rotor casings 5 and 6 is located the rotor 7 mounted on shaft 8 and being driven in the usual way by steam led 75 from inlet pipe 9 to a plurality of nozzles, as shown in my prior patent and also in my co-pending application Serial No. 193,167, filed September 25, 1917.

As shown in my application above referred to, I provide means for cooling the shaft on either side of the fluid chamber 4, utilizing for this purpose the principle of the ejector having an air duct 10 between the fluid chamber 4 and the inner bearing 11, 85 and also having a similar air duct 12 between the rotor and the outer or thrust bearing 13, the former having an aspirating nozzle 14 and the latter a similar nozzle 15. The inlet to the duct 10 is shown at 16, and 90 the inlet to duct 12, at 17. The external face of the inner half of the rotor housing or that face toward the impeller 18 is curved in accordance with the principles set forth in my prior patent before mentioned and is 95 formed with an internal chamber 19 communicating with the air-duct 10 through the inlet 20 and outlet 21, providing for the cooling of the tube 22 which forms a continuation of the oil chamber 23 for the inner 100 bearing.

Referring now to Fig. 2, the leakage arresting means is shown consisting of a pair of carbon blocks 24 each of which is inclosed in an aluminum case 25 having an annular lug 26 to form a bearing surface for the 105

spring 27 which maintains the blocks and casing separated and also in contact with the walls of the cooling chamber in the air duct 12 or 10, Fig. 2 showing the left hand or outer duct 12. These carbon seals do not revolve with the shaft 8, but simply move up and down, or sidewise, to meet the exact alignment of the shaft and are so moved by the shaft itself when the latter begin to revolve, after which the shaft revolves within the carbon seal or cylinder without any appreciable wear on either, the carbon cylinder being self-lubricating, that is, it needs no oil or other lubricant, and while it is a fairly close fit on the shaft, it is not, as shown in the drawings, a tight fit. The spring 27 thrusts the two cylinders apart until their outer ends 28 press sufficiently hard against the immovable shoulders 29, against which they are designed to rest, thereby forming practically tight joints at these points, preventing the passage of steam from the cooling chamber 30 to the bearing 13.

Steam passing through the nearer block 24, between that and the shaft 8, escapes through the space 31 between the two cases 25 and is carried away through the air duct 12 by the current of air which is induced in the aspirating nozzle or ejector 15 which is located within the stream of air being carried into the ashpit by the impeller 18.

In this way it will be noticed that the currents of air passing through the ducts 10 and 12, not only cool the shaft and the seals, but also carry away the escaped steam or condensate from the fluid chamber 4, rendering positive the diversion of such steam from the bearings.

I find it convenient to employ a pair of the carbon seals 24 in each of the cooling chambers 30, but if desired I may use only the outermost of these carbon seals and extend the spring 27 against the wall of the rotor chamber, so that the single carbon block would form a steam-tight connection against the opposite wall, *i. e.*, the wall nearest the bearing from which it is desired to divert the steam.

What is claimed is:

50. 1. A fluid chamber, a shaft passing there-

through and having a journal spaced therefrom, a duct surrounding said shaft and located between the chamber and the journal, means for causing a circulation of air through said duct, and means for diverting the flow of escaped fluid to said duct and from said journal.

2. A fluid chamber, a shaft passing therethrough and having journals spaced therefrom, ducts, surrounding said shaft and located on either side of said chamber between same and the adjacent journal, means for causing a circulation of air through said ducts, and means for diverting the flow of escaped fluid to said ducts and from said journals.

3. A fluid chamber, a shaft passing therethrough and having a journal spaced therefrom, a duct surrounding said shaft and located between the chamber and the journal, means for causing a circulation of air through said duct, and a pair of spaced blocks for diverting the flow of escaped fluid to said duct and from said journal.

4. A fluid chamber, a shaft passing therethrough and having a journal spaced therefrom, a duct surrounding said shaft and located between the chamber and the journal, means for causing a circulation of air through said duct, a pair of leakage arresters for diverting the flow of escaped fluid to said duct and from said journal, and means for maintaining the arresters in sealing contact with opposite walls of said duct.

5. A steam chamber, a high speed shaft passing therethrough and having a journal bearing on one side of said chamber and spaced therefrom, a cooling duct between the chamber and said bearing, means for causing a circulation of air through said duct, a pair of leakage arresters in said duct, each encircling the shaft but exposing the shaft to the cooling air between them, and means for maintaining the arresters in sealing relation with opposite walls of the duct and spaced apart, thereby providing space to permit the shaft to divert the escaped steam from the bearing by centrifugal action.

WILLIAM McCCLAVE.
